UNITED STATES PATENT OFFICE.

HENRY M. SHEER, OF QUINCY, ILLINOIS.

OIL-CONTROL VALVE.

1,389,075.

Specification of Letters Patent. Patented Aug. 30, 1921.

Application filed July 10, 1920. Serial No. 395,421.

To all whom it may concern:

Be it known that I, HENRY M. SHEER, a citizen of the United States, residing at Quincy, in the county of Adams and State of Illinois, have invented certain new and useful Improvements in Oil-Control Valves, of which the following is a specification.

My invention relates to an improvement in oil control valves for incubators and brooder heaters, and this invention includes a construction in its make-up which has three adjustments, to wit the minimum and maximum adjustments as now used, with a third auxiliary adjustment by means of which the needle-valve which controls the oil flow can be closed at any time without changing or deranging in any way the minimum and maximum adjustments already made.

If the operator wishes to work on his burner and shut off the oil, he does this with the auxiliary adjustment, leaving his maximum and minimum adjustments unchanged. After he shall have completed his work and starts up the burner again, he has his adjustment already made, and consequently all he need do is to open the valve by changing the auxiliary adjustment, and thus control the oil by this adjustment until the burner is thoroughly generated and is ready to take the maximum amount of oil, as per his original or previous adjustment at the maximum screw.

In this particular, the present invention entirely overcomes certain objections heretofore raised, which required considerable time in the making of re-adjustments when the light was extinguished, all of which is rendered unnecessary when the valve is equipped with this auxiliary adjustment.

The foregoing and other features of novelty will be illustrated, described and claimed hereinafter.

In the accompanying drawings:—

Figure 1 is a view in perspective;

Fig. 2 is a section;

Fig. 3 is a detail of the operating levers and adjusting screws;

Fig. 4 is a fragmentary view of the operating levers.

A, represents a bracket adapted to be secured beneath and support the oil font (not shown). At one end, the visible oil feed opening 1 is formed, through which the oil drips or is fed under control through the nipple 2, and a pipe 3 leading out of the

bottom of the visible feed opening conducts the oil to the burner (not shown).

Mounted on top of the visible oil feed opening 1, and secured thereto, is a casting 4. While this fastening might be effected in any approved manner, I prefer as a simple means of accomplishing it the use of a tubular nut 8, which screws on the external threads of the nipple 2 into a hole 9 formed therefor.

The casting 4 is counterbored through the longitudinal center to form an oil duct 5, which leads to, and discharges into, the nipple 2. This oil duct, it is understood, is tapped into the oil font (not shown) and preferably has the usual oil filter 6 secured at its inner end.

A spring actuated needle-valve 7 operates in the bore of the casting 4 for controlling the passage of oil through duct 5 and nipple 2, and the outer end of the stem of this valve protrudes beyond the casting, as shown, for a purpose that will be hereinafter fully described.

Oil is prevented from finding its way past the needle-valve when opened by the little cork or leather washer 10 at bottom end of the duct 5, and this packing is held in position by the tension of the spring.

The casting 4 is provided with an upwardly and horizontally-extending projecting arm 11 at the top, and this carries the minimum and maximum adjusting screws 12 and 13, respectively, they being located at a point where they are easily accessible and convenient to manipulate. At its lower end and beneath the valve 7, the casting has a pair of lugs 14.

The valve controlling lever 15 is fulcrumed between these lugs 14 on the pin 16, the arm of this lever above the fulcrum extending in the path of, and in close proximity to, the protruding end of the needle-valve 7, and its extreme upper end in the space between the inner end of the minimum and maximum adjustment screws 12 and 13, by which its adjustment is regulated. An auxiliary lever is also fulcrumed on the pin 16 along side the control lever 15, and its upper end also extends into the path of the protruding end of the needle-valve 7. This auxiliary lever 17 has a flange 18 at one edge which overlaps the outer edge of the lever 15, so that when lever 15 swings in one direction, the auxiliary lever 17 moves with it, whereas the latter is free to swing independ-

ently of lever 15 in one direction, as is also lever 15 independently of lever 17 in one direction.

5 An auxiliary adjustment screw 19 screws into the threaded eye 20 at the lower end of the auxiliary lever 17.

By means of the auxiliary lever, the needle-valve can be opened or closed without deranging or changing in the least the 10 position of the minimum and maximum adjusting screws 12 and 13 at the top of the valve. Without this auxiliary adjustment 15 19, it is necessary to use the maximum adjusting screw to close the valve 7 and shut off the oil; and of course this also makes it necessary to change the position of the minimum adjusting screw 12. In other words, 20 without the auxiliary adjustment it was necessary to change the maximum and minimum screws every time the operator wished to give the burner attention, and then after re-lighting he had to go through the entire process of re-adjustment. With the auxiliary 25 adjustment, the previous adjustment of the maximum and minimum screws remains unchanged, so there is nothing further to do, after giving the burner attention, but to start it, providing oil by means of the auxiliary adjustment until the burner is generated, then entirely releasing the auxiliary 30 screw, and the valve will then function according to the previous adjustments.

I claim:

1. The combination of an oil pipe, means 35 for discharging oil thereinto, a valve for controlling the flow of oil, two levers in position to control the valve, said levers constructed and adapted to move independently of each other in one direction, and in position to actuate the valve, and adjustment 40 screws for each of said levers.

2. The combination of a support, a casting 45 having a duct therein, and a needle valve in said duct, a control lever, and an auxiliary lever fulcrumed at a common point extending in the path of the valve, whereby to actuate the valve, and minimum and maximum and auxiliary adjusting screws connected with said levers for controlling the 50 needle-valve.

3. The combination of a support, a casting secured thereto, two levers pivoted to the casting, one carrying an auxiliary adjustment screw in position to be forced against

the support, minimum and maximum screws 55 carried by the casting for regulating the movement of the main lever, and a spring-actuated valve carried by the casting in the path of said levers.

4. The combination of a visible oil feed 60 opening, a casting secured thereon, said casting counterbored to form an oil duct which discharges into the visible oil feed opening, a spring-actuated needle-valve in said duct, one end of which protrudes beyond the surface of the casting, the casting having an arm and lugs, two levers pivoted side by side to the lugs with portions in the path of the protruding end of the valve, said levers capable of moving together in one direction 65 and independently in the other, an auxiliary adjustment screw carried by the auxiliary lever, and a minimum and maximum screw adjustment in the arm of the casting for regulating the position and movement of the 70 main lever.

5. The combination of a visible oil feed opening, a nipple extending thereto and discharging therein, a casting having a duct 75 therein in communication with the nipple, a spring-actuated needle-valve for controlling the flow of oil through said duct, one end of said needle-valve protruding beyond the casting, two levers pivoted side by side to the casting, an auxiliary adjustment screw 80 carried by one of said levers, and maximum and minimum adjustment screws in the casting on either side of the other lever for regulating the position and vibrations of said 85 lever.

6. The combination of a visible oil feed opening and a casting having a duct therein and a nipple in communication with the duct in position to extend into the visible oil feed 90 opening, said nipple externally screw-threaded and a tubular nut which screws on the threads of the nipple into a socket in the visible oil feed opening for securing the casting thereon.

7. The combination with a visible oil feed 95 opening and a casting secured thereto, said casting counterbored to form a duct, of a spring-actuated valve slidable in said duct, the duct having a washer therein which is held in position by the tension of the spring 100 of the valve.

In testimony whereof I affix my signature.
HENRY M. SHEER.
